CLAIM

I claim the ornamental design for a chair, as shown and described.

DESCRIPTION

FIG. 1 is a front perspective view for a chair of my design;

FIG. 2 is a rear perspective view thereof;

FIG. 3 is a front elevation view thereof;

FIG. 4 is a right side view thereof;

FIG. 5 is a left side view thereof;

FIG. 6 is a rear elevation view thereof;

FIG. 7 is a top view thereof; and,

FIG. 8 is a bottom view thereof.

Dashed lines indicate stitching that is not claimed as part of my design.
